Patented Sept. 27, 1921.

Carl Fischbauer

UNITED STATES PATENT OFFICE.

CARL TEICHTNER, OF LEIPZIG, GERMANY.

PERMANENT CALENDAR.

1,391,917.

Specification of Letters Patent. Patented Sept. 27, 1921.

Application filed February 19, 1920. Serial No. 359,961.

To all whom it may concern:

Be it known that I, CARL TEICHTNER, a citizen of the German Republic, and a resident of Leipzig, Germany, manufacturer, 5 have invented certain new and useful Improvements in a Permanent Calendar, for which I have filed applications in Germany Oct. 26, 1918; Germany additional Jan. 27, 1919; Hungary Feb. 17, 1919, and Switzerland Feb. 8, 1919, of which the following is 10 a statement.

The present invention relates to a new permanent calendar, which may be used for any year, and may also, if desirable, be 15 conveniently carried in the pocket; the calendar may, however, also be made to stand on a writing desk or to be hung on a wall.

In the accompanying drawings wherein like symbols designate like parts throughout 20 the several views,

Figure 1 is a top plan view of one form of permanent calendar constructed according to the present invention and shown in open position;

25 Fig. 2 is a similar view with the cover closed;

Fig. 3 is a plan view of a slightly modified form of the calendar in open position;

Fig. 4 is a similar view showing the same 30 device closed;

Fig. 5 is a view in front elevation of a further modified form of calendar constructed according to the present invention; and

Fig. 6 is an edge view thereof.

35 On the right-hand inner side of a book-cover-like folder a small booklets h^1 , h^2 , h^3 are fitted, on the leaves of which the various data are printed. So, for example, the leaves of booklet h^1 show the date 1-31 of each month. The leaves of booklet h^2 show 40 the twelve names of the months, and the leaves of booklet h^3 the names of the days of the week.

The one half of the said folder a is provided with windows b^1 , b^2 , b^3 which are so arranged, that when the folder is closed, the date, the month and the respective day may be read, as seen in Fig. 2.

50 Figs. 3-4 illustrate another modification of the invention, showing only the date and the month.

Here only the two booklets h^1 and h^2 are employed, of which booklet h^1 is turned over from right to left while booklet h^2 is 55 turned over from up down. The windows in the cover part of the folder are arranged

to correspond with the printed pages of the said booklets, so that the date and the month may be read as seen in Fig. 4. The said windows b^1 , b^2 , b^3 may be either left 60 open, or be fitted with a transparent sheet of suitable material.

On the pages of the said booklet, which do not bear any of the calendar indications, advertisements or verses and the like may 65 be printed. The user of the calendar will read these when turning over the leaves of the said booklets.

The closed folder is held in such position by aid of suitable clasps or similar means. 70

Figs. 5 and 6 illustrate in elevation and vertical section, respectively, another modification to be used as standing or wall calendar. In this modification the booklets h^1 , h^2 , h^3 are arranged in form of terraces. 75 Here, however, the turned over leaves are not held by the one half of a cover, as with the hereinbefore described form, but by flaps k^1 , k^2 , k^3 specially provided to fall over the leaves f^1 , f^2 , f^3 of the booklets h^1 , h^2 , h^3 , when these have been turned upward, and thereby prevent them from falling down again. The said flaps k^1 , k^2 , k^3 extend about down to the middle of the said booklets, so that they clear the pages 80 thereof, bearing the dates, months and days. On these flaps, and on the back of the leaves bearing said data advertisements and the like may be printed. This form of the calendar may also be so made that extensions 85 are provided at top and bottom or at the sides thereof, or only at one of these parts of the foundation g , on which extensions permanent advertisements may be arranged. 90

The flaps k^1 , k^2 , k^3 which may be painted 95 or printed with advertisements, may be made, instead of paper, also of thin wood, sheet metal or other suitable material.

I claim:

1. A permanent calendar comprising a 100 supporting backing, individual booklets or pads containing data indicating independently the day and month of the year, the leaves of said pads or booklets being printed with the data on one side only, the leaves of 105 the pads adapted to be turned over successively to expose new data, and retaining means supported by said backing and being openable away from the backing to permit the operator to have access to the booklets 110 or pads for the purpose of turning the leaves over, said retaining means adapted

to engage completely the turned-over leaves and to obscure such turned-over leaves but exposing the data on the leaves not yet turned over.

- 5 2. A permanent calendar comprising a backing member, a series of pads or booklets arranged in stepped or terraced relation on said backing and provided with data indicating the month, day of the week, 10 and number of the day respectively, said pads or booklets having the leaves adapted to be turned over for exposing new data, and a series of flaps also arranged in terraced relation supported from said backing

member and adapted to extend in front of 15 the upper portion of said pads without obscuring the data thereon but adapted to hold the folded up leaves in place, said flaps being yieldable outwardly to permit turning of the leaves of the booklets or pads 20 upwardly.

In testimony whereof I hereunto affix my signature in the presence of two subscribing witnesses.

CARL TEICHTNER.
